Mary E. Boice,

By *Watson E. Coleman.* Attorney

UNITED STATES PATENT OFFICE.

MARY E. BOICE, OF ALEXANDER, NORTH DAKOTA.

DISH-RECEPTACLE.

1,028,320.

Specification of Letters Patent.

Patented June 4, 1912.

Application filed February 5, 1912. Serial No. 675,436.

To all whom it may concern:

Be it known that I, MARY E. BOICE, a citizen of the United States, residing at Alexander, in the county of McKenzie and State 5 of North Dakota, have invented certain new and useful Improvements in Dish-Receptacles, of which the following is a specification, reference being had to the accompanying drawings.

10 My invention relates to new and useful improvements in the art of kitchen and table articles and more particularly to a dish rinsing and drying device, and my object is to provide a device within which dishes, 15 knives, forks, spoons and the like may be rinsed and upon which said articles may be dried.

A further object of the invention resides 20 in providing a device which may be readily introduced within a dishpan in order that the articles carried within said device may be rinsed, and a still further object resides in providing means for supporting the device after removing from the dishpan so 25 that the articles carried thereon may be dried.

A still further object of the invention resides 30 in providing a device composed entirely of wire, the same being provided with wire hoops, with wire sides and bottom, 35 which wires are interwoven and soldered at convenient points to give the device strength and rigidity, and a further object resides in forming the device into a combined dish-rinsing basket or the like and dish-drying 40 tray therefor.

Another object of the invention resides in 45 providing a device which is extremely simple and durable in construction, inexpensive to manufacture, and one which is very efficient and useful in operation.

With these and other objects in view, my 50 invention consists in the novel features of construction, combination and arrangement of parts as will be hereinafter referred to 45 and more particularly pointed out in the specification and claims.

In the accompanying drawing forming a 55 part of this application, Figure 1 is a top plan view of the device. Fig. 2 is a vertical section therethrough as seen on line 2-2. Fig. 1. Fig. 3 is an enlarged fragmentary section through the device, showing the particular arrangement of wires, and, Fig. 4 is a fragmentary perspective view showing a 55 slightly modified form of supporting member for the device.

In carrying out my invention, I shall refer to the drawing in which similar reference characters designate corresponding parts throughout the several views and in 60 which—

1 and 2 indicate, respectively, the lower and upper hoops of a wire basket, the lower hoop being of smaller diameter than the upper and provided with a plurality of interwoven wires 3, the ends of which are bent into engagement with said hoop 1 and soldered for rigidity, and forming the sides of the basket between the upper and lower hoops thereof, are the interwoven substantially vertical and horizontal wires 5 and 4, the vertical wires being bent at their lower ends around the hoop 1 and also soldered thereto, while the upper ends of the same are extended over the upper hoop 2 and project radially and horizontally therefrom. The interwoven wires 3 with the hoop 1, 70 form a bottom for the basket, while the interwoven wires 5 and 4 form sides for the same, it being understood that this basket 75 will permit of dishes, knives and forks and the like being rinsed therein while the device is placed within a dish-pan, and I have provided for the drying of the articles rinsed within this basket by forming a tray 80 thereon. To this end, I provide an additional hoop 6 which is of a larger diameter than the hoop 2 and disposed on the same horizontal plane therewith, said hoop 6 receiving in engagement therewith, the wires 85 5 which are extended over the hoop 2, said extensions 5 of the wires continuing upwardly from the hoop 6, to be bent in engagement and soldered with an additional hoop 8 which is of a larger diameter than the 90 hoop 6 and disposed some distance thereabove.

From this construction, it will be seen that 95 the basket formed by the lower and upper hoops 1 and 2, respectively, the bottom wires 3 and the side wires 4 and 5 will permit of the articles being rinsed therein while said basket is disposed within the dish-pan or the like, and that portion of the same formed by the horizontal and upward extensions of 100 the wires 5 and the lower and upper hoops 6 and 8 will permit of the articles being placed thereon after being rinsed, in order to dry. To this extent, this latter portion 105 of the device forms a drying tray, and in 110 order to prevent articles placed thereon from passing to the basket I provide a

fender or the like which comprises a hoop member 9 of a diameter substantially the same as the hoop 2, which is supported immediately above said hoop 2 by means of the 5 supporting wires 10, said latter wires being bent into engagement with the hoop 9 at their upper ends, while the lower portions of the same are soldered or otherwise secured to the hoop 2.

10 As stated above, this device may be introduced in a dish-pan or other receptacle so that the water therein may be used for the rinsing of the articles carried within the basket portion of the device, and in order 15 to provide a supporting means for the device while in the referred to position and also to support the device after being removed from the dish-pan, I provide a hoop or base member 11, with which are engaged 20 at regular intervals therearound, a plurality of arms 12, said arms being bent around said hoop 11 to form a pivotal connection therewith. The upper end of each arm 12 is bent and curved inwardly to form a substantial 25 hook portion 13, which hook portions of said arms 12 are adapted to receive in engagement therewith, the upper hoop 8 of the drying tray, and in order to retain these arms 12 in a substantially vertical position 30 so as to position the device above the base hoop 11 and prevent any wabbling of the device when set up, I provide the supporting braces 14, one of which is pivotally mounted to each of the arms 12 adjacent its 35 lower end. These braces 14 are adapted to be disposed in their extended positions by means of coil spring members 15 which are engaged, respectively, with the arms 12 and braces 14, but in order to retain said braces 40 against the arms 12 when the device is not in use, I provide the ring members 16 loosely disposed on the arms 12 which may be drawn over the braces 14 to retain the same against the arms 12. Thus, the device for rinsing 45 and drying the dishes and other articles, may be readily supported above the dish-pan so that portions of the basket may be disposed therewithin and may also be supported beyond the dish-pan after the rinsing 50 has been completed, by merely setting up the supporting device. While this supporting device, as described, is the essential form of the device, I have also provided a modified form which comprises a base hoop 11' 55 to which is secured the lower ends of a plurality of supporting arms 12', the lower ends of said arms 12' being bent in engagement with the hoop 11' and soldered thereto, while the upper ends of the same are bent in engagement and soldered with a hoop 8', said hoop 8' representing the upper hoop of the 60 drying tray of the device. These arms 12' being soldered, as described, to the hoops 11' and 8', will rigidly support the device 65 at all times.

In order that the device may be carried from place to place and handled quite readily, the handle members 17 are provided which are carried on the upper hoop 8 at diametrically opposite points thereon. While 70 such handle members are not shown in the modified form, it will be understood that the same are also provided, and in fact, all matter other than the supporting device, as shown in the preferred form, is also provided in this modified form, it being understood that the modification is merely as regards the supporting arms.

In practice, when it is desired to use the preferred form of my invention, the arms 12 of the supporting members are brought to a substantially vertical position and the upper hoop 8 engaged with the hoop portions 13 of said arms, whereupon the bases 14 on the arms 12 are allowed to be disposed to their 80 extended positions thereby supporting the arms in their vertical positions when the braces are positioned on a support. The various articles to be rinsed may then be placed in the basket portion of the device and the 85 complete device disposed over a dish-pan or other receptacle containing water, so that the base hoop 11 encircles the receptacle while the basket portion of the device is 90 partially introduced therewithin. It will 95 be understood that the braces resting on the support upon which the base hoop 11 is mounted, will rigidly support the arms 12, which will permit the device proper to be 100 properly carried thereon, and the articles 105 within the basket may then be thoroughly rinsed, and as the rinsing of each is completed, said articles are placed on the tray 110 of the device. In this connection, I prefer 115 to use various cloths which are to be disposed on the wires 5 forming the base or flooring of the tray, so that the drops of water dripping from the articles will pass to these cloths to be absorbed thereby. When all the articles have been rinsed and 120 placed upon the tray, the complete device may be lifted from its position over the receptacle and supported in any other place, whatsoever, to allow the articles to completely dry in their positions on the tray. As stated, the operation of this device, as 125 described, has connection with the preferred form, that is the knockdown supporting means for the device, but it will be understood that in the modified form wherein the supporting means is formed rigid with the basket and tray portion of the device, the operation will be the same as in the other form except for the fact that there will be no necessity for the setting up of the 130 supporting means. In the preferred form, after the dishes and other articles have been thoroughly dried by being allowed to stand upon the tray, the same may be removed therefrom to their proper places, and the 135

device knocked down and placed away for further use. In the folding of the device, it will be seen that after the basket and tray portion of the device has been removed from the supporting device, the braces 14 may be brought to their contracted positions against the arms 12, whereupon said arms may be folded against the hoop 11 and with the other portion of the device, compactly placed away for further use.

From the foregoing, it will be seen that I have provided a simple, durable, inexpensive and efficient means for carrying out the object of the invention, and while I have particularly described the elements most well adapted to perform the functions set forth, it is obvious that various changes in form, proportion and in the minor details of construction may be resorted to without departing from the spirit or sacrificing any of the principles of the invention.

What I claim is:—

1. A rinsing and drying device, comprising a receptacle formed of wire, a tray portion formed at the upper end thereof, and a supporting means for the device.

2. A rinsing and drying device, comprising a receptacle formed of wire, a tray formed on the upper portion of said receptacle, and supporting means for the device, said supporting means so disposing the device as to position the lower portion of the receptacle above the base portion of the supporting means.

3. A device of the class described, comprising a wire receptacle, a tray portion also formed of wire and surrounding the upper

portion of said receptacle, and a supporting means for the device comprising a base portion, and arms carried thereon engaging said tray, said supporting means so disposing the device as to position the lower portion of the receptacle above the base portion of the supporting means.

4. A device of the class described, comprising a receptacle formed of wire, a tray portion formed at the upper end thereof and surrounding the same, certain of the wires forming the sides of said receptacle being continued to form the base portion and sides of said tray, a supporting means comprising a hoop, and arms carried thereon and engaged with the upper portion of the tray, said supporting means so positioning the device as to position the lower portion of the device above the base portion of the supporting means.

5. A device of the class described, comprising a wire receptacle, a tray also formed of wire and surrounding the upper portion of the receptacle, a supporting means for the device comprising a base hoop, arms pivotally carried thereon, the upper ends of said arms being adapted for engagement with the upper portion of said tray, and means to support said arms in their upright positions.

In testimony whereof I hereunto affix my signature in the presence of two witnesses.

MARY E. BOICE.
